Patented Oct. 13, 1959

186,330

BICYCLE HEADLIGHT

Daniel M. Pearl, Skokie, Ill.

Application May 8, 1958, Serial No. 50,801

Term of patent 14 years

(Cl. D48—24)

Fig. 1.

Fig. 2.

Fig. 3.

Fig. 4.

Fig. 1 is a top plan view of a bicycle headlight showing my new design.

Fig. 2 is a side elevational view thereof.

Fig. 3 is an end elevational view looking from the left of Fig. 2.

Fig. 4 is an end elevational view looking from the right of Fig. 2.

The dominant features of my design reside in the portions shown in full lines:

I claim:

The ornamental design for a bicycle headlight, substantially as shown and described.
